UNITED STATES PATENT OFFICE.

COMMIE L. ENNIS, OF BOYKINS, VIRGINIA.

LAMP HANGER.

Application filed November 20, 1924. Serial No. 751,090.

To all whom it may concern:

Be it known that I, COMMIE L. ENNIS, a citizen of the United States, residing at Boykins, in the county of Southampton and 5 State of Virginia, have invented a new and Improved Lamp Hanger, of which the following is a specification.

The invention generally relates to railroad warning lamp hangers and resides in 10 the provision of a hanger bracket adapted to be mounted upon a railroad crossing guard arm for suspending a lamp therefrom in a manner obviating the danger of breakage of the lamp by free swinging against the 15 said guard arm and being so constructed that when operatively mounted the same will not induce torsional or lateral strain of the guard arm.

The novel details of construction of the 20 invention will be first fully described, then be all specifically pointed out in the appended claims and illustrated in the accompanying drawing, in which:—

Figure 1 is a perspective view illustrating 25 the manner of mounting the invention upon a crossing guard arm.

Figure 2 is a side elevation illustrating the invention in operation.

Figure 3 is a detail cross section of the 30 hanger bracket per se.

In the drawing, in which like numerals of reference indicate like parts in all of the figures, 1 indicates the railroad crossing guard arm. The guard arm is of that type 35 which is vertically-swingably mounted upon a control housing to be lowered horizontally across the road, guarding the same during the passage of a train, and for being elevated to a substantially vertical position when not in use for the purpose just described.

In the use of common types of lamp hangers in connection with crossing guard arms great loss is occasioned by the free swinging 45 of guard lamps suspended therefrom against the said arms, resulting in breakage of the encasing globe or other parts of the structure.

The bracket forming the principal part of 50 my present invention is preferably shaped up from a single sheet of spring metal to include a main plate portion 2 bifurcated as at 3 to straddle the guard arm 1 and having extensions 4 shaped as at 5 to provide pivot hinge portions adapted to cooperate with the cross bolt or pivot shank 6 inserted

through the guard arm 1 in the manner illustrated in Figure 1 of the drawing.

That portion of the metal of the plate from which the bracket is formed which 60 was cut to provide the bifurcation is bent backwardly and downwardly to provide a more or less resilient abutment finger 7.

The main body 2 of the bracket is bent back upon itself as at 8 to provide a plate 65 portion 9 for opposing the main body portion 2 and cooperating therewith in providing a lamp bail receiving pocket therebetween. This plate portion may be shaped as illustrated in Figure 1 of the drawing so 70 that when the bail 10 of the warning lamp is inserted into the pocket formed between the said plate 9 and body portion 2, it will be restricted from free movement and to lie in a plane with the said body and plate 75 portions.

When the bracket above described is pivotally connected to the guard arm 1, as at 6, the lamp will be mounted thereupon in a pendent manner and freely swingable 80 to a certain degree.

It will be observed, by reference to Figure 2 of the drawing, that when the guard arm 1 is elevated to its approximately vertical position the resilient abutment finger 7 will 85 engage the underside of the said guard arm and act to throw the bracket outwardly on its pivot 6 away from contact with the said guard arm, thus preventing such free swinging 90 of the lamp as will cause damage thereof by forcible engagement with the said guard arm.

By thus suspending the bracket directly from and centrally of the bottom edge of 95 the guard arm 1, its weight is balanced and there is no tendency toward twist or lateral strain of the guard arm.

From the foregoing description, taken in connection with the accompanying drawing, it is thought the novel details of construction, manner of use and the advantages of my invention will be readily apparent to those skilled in the art to which it relates.

What I claim is:

1. In combination with a railroad crossing guard arm and a signal lamp having a swinging bail a hanger pendently secured to the arm to swing freely beneath it, said hanger including a member for holding the bail of the lamp, and also including a resilient member to engage the guard arm when said guard arm is in an elevated posi- 105 110 115

tion substantially as shown and described.

2. A lamp hanger comprising a plate having ears to straddle a crossing guard arm and by which ears it may be pivotally mounted on an arm, said plate having a portion bent back upon itself to constitute a hook to receive a lamp bail, and a member carried by said plate and adapted to engage the arm on which the hanger is mounted when said arm is elevated toward a vertical position.

3. In combination with a crossing guard arm, a lamp hanger comprising a body having members adapted to project to either side of the guard arm, means pivotally securing said members to the guard arm whereby the hanger will be pendent from and lie beneath the guard arm, said hanger including means for holding the bail of a

signal lamp substantially rigid, and means 20 carried by said hanger for resiliently engaging the guard arm when the same is elevated whereby the lamp will be held away from the guard arm substantially as shown and described.

4. In combination with a crossing guard arm which is adapted to be moved to a horizontal or to a vertical position as desired, a signal lamp and means for mounting said lamp directly beneath said guard arm, said mounting means including mechanism 25 for holding the lamp away from the guard arm when the guard arm is elevated, the axis of the lamp remaining at all times in the plane in which the guard arm has movement.

COMMIE L. ENNIS.
